United States Patent

Des. 236,706
Patented Sept. 9, 1975

236,706

AUTOMOBILE

Sergio Pininfarina, Turin, Italy, assignor to Rolls-Royce
Motors Limited, Crewe, England

Filed Nov. 16, 1973, Ser. No. 416,494

Term of patent 14 years

Int. Cl. D12—08

U.S. Cl. D12—92

FIG. 1

FIG. 2

FIG. 3

FIG. 4

FIG. 1 is a front elevational view of an automobile showing my new design;

FIG. 2 is a rear elevational view thereof;

FIG. 3 is a side elevational view thereof; and

FIG. 4 is a front perspective view thereof.

The side opposite to that shown in FIG. 3 is substantially a mirror image of the side shown therein.

I claim:

The ornamental design for an automobile, as shown and described.
